M. MEIER.
ADJUSTABLE VIOLIN SHOULDER SUPPORT,
APPLICATION FILED MAR. 19, 1918.

Patented Mar. 11, 1919.

INVENTOR,
Marcel Meier
BY
W. H. Randall
ATTORNEY.

UNITED STATES PATENT OFFICE.

MARCEL MEIER, OF LOS ANGELES, CALIFORNIA.

ADJUSTABLE VIOLIN SHOULDER-SUPPORT.

1,296,831.

Specification of Letters Patent. Patented Mar. 11, 1919.

Application filed March 19, 1918. Serial No. 223,426.

To all whom it may concern:

Be it known that I, MARCEL MEIER, a citizen of the United States, residing at Los Angeles, in the county of Los Angeles and 5 State of California, have invented a new and useful Adjustable Violin Shoulder-Support, of which the following is a specification.

This invention relates to a violin support and its object is to provide an attachment 10 for a violin whereby the latter may be readily supported between the chin and shoulder of the player without cramping the neck muscles and in such manner as to permit freedom of movement and facilitate technic 15 of the left hand.

Another object is to provide a violin support which may be detachably connected to a violin and held in place thereon by means of the ordinary chin rest and which may be 20 adjusted either before or after attachment to vary the position of the support portion relative to the violin so as to adapt it to the shoulder of the player and insure correct positioning of the instrument in playing.

25 Other objects will appear hereinafter.

The invention is illustrated in the accompanying drawings, in which:

Figure 1 is a perspective view of the violin support as removed.

30 Fig. 2 is an end view of same showing it as applied and illustrating the manner of attaching it to a violin by means of the chin rest.

Fig. 3 is a perspective view of a violin 35 illustrating the invention as applied.

In carrying out the invention the support is formed with a curved attachment band 5 adapted to lie against the end face of a violin and to be interposed between the violin 40 and turn-buckles 7 by which the ordinary chin rest 8 is attached to the violin; the turn-buckles bearing against the attachment band 5 to hold the latter in place. As a means for effecting a clamping action by 45 the turn-buckles on the attachment band, the latter is formed with a bend 9 and an offset end portion 10, and is provided with a bearing plate 11 on the end opposite the offset portion 10. The intermediate portion of 50 the band is thus bowed outwardly spring fashion so that when this bowed portion is interposed between the violin and the turn-buckles with the latter pressing thereagainst

tending to flatten same, a clamping action is obtained.

55 Connecting with the bowed portion of the attachment plate is a substantially V-shaped bracket 12 which extends downwardly from the band thence upwardly and terminates in a padded outer end 13 adapted to bear 60 against the under side or back of the violin at a point remote from its edge. A resilient pad 14 is disposed at the juncture of the side portions with the bracket, which pad is positioned to rest against the shoulder of the 65 player.

As a means for varying the position of the pad 14 relative to the violin so as to raise or lower it to suit the shoulder of the player means are provided for spreading the side 70 members of the bracket apart or to draw them together. This means comprises a pair of tangs 15 struck from the side members of the bracket and extending toward each other. The tangs 15 have parallel flanges 75 16 on their outer ends through which a threaded stem 17 passes. A knurled nut 18 is screwed on the stem and is adapted to be advanced or retracted thereon so as to draw the side members of the bracket together or 80 permit them to spread apart.

In the application of the support it is positioned on the violin with the band 5 engaged by the turn-buckles 7, of the chin rest and with the pad 13 bearing against the 85 violin back, as shown in Fig. 3. This disposes the shoulder pad 14 in proper relation to the violin back and in a firm position by reason of the brace afforded by the spreading side members of the V-shaped bracket 90 12 and their adjustable connection.

The pad 14 upon the bracket 12 provides a firm non-slipping support for the violin when the latter is interposed between the shoulder and chin and pressure brought to 95 bear on the chin rest and insures the instrument being held in the correct position for playing. This permits the violin being held without the aid of the left hand and leaves the hand free for fingering without supporting the violin, thus facilitating technic.

As a means for adjusting the bracket 12 relative to the band 5, the bracket is attached to the band 5 by means of the pivotal connection, comprising the threaded stud 19, 105 on the band 5 which passes through the

bracket, and is fitted with a nut 20, by means of which the bracket and strap may be clamped together, and disposed at various angular positions relative to each other, as occasion may require.

I claim:

1. The combination with a violin and a chin rest thereon, of a shoulder support, said shoulder support comprising an attachment member held in place on the violin by the chin rest, a V-shaped dependent bracket on said attachment member adapted to seat on the shoulder of a player, and means for spreading or contracting the side members of the bracket.
2. The combination with a violin and a chin rest thereon, of a shoulder support, said shoulder support comprising an attachment

member held in place on the violin by the chin rest, a V-shaped dependent bracket on 20 said attachment member adapted to seat on the shoulder of a player, and a non-slip pad arranged at the juncture of the side members of said bracket.

3. The combination with a violin and a 25 chin rest thereon, of a shoulder support, said shoulder support comprising an attachment member held in place on the violin by the chin rest, a V-shaped dependent bracket on 30 said attachment member adapted to seat on the shoulder of a player, a non-slip pad arranged at the juncture of the side members of said bracket, and means for adjusting the angle between the side members of the bracket.

MARCEL MEIER.
